UNITED STATES PATENT OFFICE

WARREN L. BOYER, OF KINGSTON, NEW YORK, ASSIGNOR TO BEMIS CAR TRUCK COMPANY, OF SPRINGFIELD, MASSACHUSETTS, A CORPORATION OF DELAWARE.

BRAKE-HEAD.

1,152,391.

Specification of Letters Patent.

Patented Sept. 7, 1915.

Application filed September 29, 1913. Serial No. 792,322.

To all whom it may concern:

Be it known that I, WARREN L. BOYER, a citizen of the United States, and a resident of Kingston, in the county of Ulster and 5 State of New York, have made and invented certain new and useful Improvements in Brake-Heads, of which the following is a specification.

My invention relates to an improvement 10 in brake heads, that is, to a device designed to support a brake shoe in proper relation to the tread or periphery of the wheel of a railway car or similar vehicle. In the manufacture of brake shoes and brake heads, it 15 was formerly the custom to construct these two parts or elements in one piece, or in the form of a single casting, the result being that when the body of the shoe had been partially worn away in service, the remaining 20 part of the casting, including the brake head, was scrapped, entailing a considerable loss. In the last few years, however, it has been the custom to make the head and shoe of separate parts, the head being secured to the brake beam, and the shoe in turn secured to the brake head, so that in the scrapping of the worn shoe the brake head is preserved for further use, excepting 25 in such instances where the head is worn and injured by coming into contact with the tread of the wheel, due to the faulty brake rigging and the resultant uneven wear of the shoe. In those instances where the wearing face of the shoe is not held parallel to 30 the tread of the wheel, one end of the shoe is rapidly worn away, the result, in many instances, being that this wear extends into the corresponding end of the brake head, causing injury both to the head and the 35 wheel with which it comes in contact. In order to obtain the best results, therefore, and to avoid, as far as possible, injury to the wheel, and to secure the highest efficiency in the brake head, it is essential that the 40 latter be made or cast from a metal which will withstand the great strains imposed upon it, especially when applied to the heavy and fast running trains of the present day, and, secondly, to construct it of a metal 45 which, should it come in contact with the tread of the wheel, will not cut or injure the same. It has been found that the use of common gray iron is impractical, owing to the fact that, in order to secure sufficient 50 strength in a cast iron brake head to resist

fracture, the head would have to be made entirely too large, as cast iron is not tough and is liable to be cracked or broken in service. Carbon steel has been employed in the casting of these brake heads, but it has been 55 found that when it happens to come in contact with the wheel it so cuts, scores and injures the tread as to necessitate the frequent dressing of the latter. It has also been attempted to employ malleable iron in the construction of a brake head, and while preferable under ordinary circumstances to carbon steel, this metal has been found objectionable by reason of its liability to become 60 bent, twisted or distorted, especially when 65 heated by its contact with the shoe, or with the tread of the wheel, when the shoe is unevenly worn away as above explained.

From frequent experiments, I have found that a brake head cast or otherwise formed from manganese steel overcomes all the objections heretofore urged against the use of other metals, in that it is sufficiently tough and strong to be capable of withstanding 70 the high stresses and strains imposed upon 75 it without the necessity of employing a large amount of metal in the construction thereof, and therefore largely avoids any danger of cracking and falling apart when in use. Furthermore, when it becomes highly heated, due to the frictional contact with the tread of the wheel, it does not bend or distort, but rapidly disintegrates, while at the same time retaining its toughness, thereby 80 avoiding any and all danger of scoring or 85 injuring the wheel.

My invention therefore consists in a brake head, cast, or otherwise formed from manganese steel, without reference to its particular type or pattern, that which I have 90 shown in the drawing being such as is ordinarily employed to support a brake shoe in proper relation to the wheel. This head is produced by well known processes, common 95 in foundry practice, and is illustrated as having a longitudinally curved surface 2, adapted to contact with the back of the shoe to be supported thereby, which curved surface is interrupted by a recess 3, into which the key lug of the shoe (not shown) extends. As is usual, a shoe is secured to the head by 100 a key or other fastening member, extending longitudinally of the head between the two rearwardly extending sides 4 thereof, the key passing through an opening in the key 105 110

lug of the shoe and through an opening 6 provided for it in the head. The rearwardly extending sides 4 are connected by a transverse wall shown at 7 to thereby provide a bracket 8 whereby the head may be secured to a brake beam, or equivalent support, the above-mentioned parts of the head, with the other features thereof necessary or desirable to produce a practical brake head, being 10 preferably made in the form of a single casting.

As I have before stated, my invention is not in any way restricted to the particular construction, form or structural details of 15 the head, as such are in no way involved therein, the gist of the invention lying in the employment of a particular metal whereby to produce certain new results, in accordance with the particular use to which the device 20 is put. Nor is my invention to be restricted to any particular composition of manganese steel, as such may vary within the limits of what is well known and termed by metallurgists as "manganese steel," and wherein. 25 relative proportions of iron, manganese, carbon, and the other constituents of the steel, may be varied, altered or changed within certain well known limits. On the other hand, it is intended that my claims shall include and cover a brake head made of any 30 and all metals, regardless of the constituents thereof, and which can be properly included

within the term "manganese steel" as defined by metallurgists and those skilled in the art.

35

Having fully described and explained my invention, I claim and desire to secure by Letters Patent:

1. A brake head adapted to support a brake shoe and formed of manganese steel, 40 which, when cold, and subjected to normal conditions, is hard and strong, and which, under abnormal conditions and when contacting with a car wheel, rapidly softens and disintegrates under the frictional heat so 45 generated.

2. A brake head adapted to support a brake shoe for contact with car wheels and made of a metal possessing the properties, 50 that when cold it is relatively harder than the wheel tread, and which when subjected to the influence of frictional heat by contact with the car wheel, rapidly softens and disintegrates, for the protection and preventing the scoring of, the said car wheel. 55

Signed at New York, borough of Manhattan in the county of New York and State of New York this 19th day of September A. D. 1913.

WARREN L. BOYER.
